UNITED STATES PATENT OFFICE.

FRANK REDICK, OF PARKERTON, WYOMING.

SAND-REEL BEARING.

Application filed January 4, 1926. Serial No. 79,254.

This invention relates to sand reels, and more particularly to a bearing therefor which is of the construction and arrangement, that the sand reel can be conveniently shifted either into contacting engagement with the periphery of the band wheel or brake, as the occasion may require.

The nature and advantages of the invention will be better understood when the following detailed description is read in connection with the accompanying drawings, the invention residing in the construction, combination and arrangement of parts as claimed.

15 In the drawings forming part of this application, like numerals of reference indicate similar parts in the several views, and wherein:

Figure 1 is a view showing the normal 20 position of the sand reel with relation to the band wheel.

Figure 2 is a view of the sand reel bearing taken at a right angle to Figure 1.

25 Figure 3 is a sectional view on line 3—3 of Figure 1.

Figure 4 is a sectional view on line 4—4 of Figure 2.

Referring to the drawings in detail, A indicates generally a band wheel of well known 30 construction which forms part of a well drilling apparatus, while B indicates generally a sand reel which is arranged to one side of the wheel A as clearly illustrated in Figure 1. The gist of the present invention resides in the construction of the sand reel bearing, and the manner of mounting said bearing, to permit the sand reel B to be conveniently moved in either direction.

The shaft of the sand reel is indicated at 40 10, and adapted to be received by a bearing 11 which is lined with Babbitt metal 12, the shaft 10 being surrounded by a set collar 13. One end of the bearing is formed with a passage 14 through which the bearing may be lubricated from time to time. Projecting from the bearing 11 at diametrically opposite points are lugs used in pairs, one pair of these lugs being indicated at 15 while the other pair is indicated at 16. The bearing 50 is adapted to be positioned within an eccentric bearing indicated generally at 17, and which bearing in turn is adapted to be arranged within a combined base and housing, the base being indicated at 18 and the housing portion at 19. The eccentric bearing 17 is recessed at spaced points about its periph-

ery as at 20 and each recess is arranged in a series of roller bearings 21 to reduce friction as will be readily understood. When the shaft bearing 11 is positioned in the eccentric bearing 17, the lugs 15 bear against lugs 22 which project inwardly from the eccentric bearing, while one of the other lugs 16 is hollow to receive the adjacent lug 23. An adjusting screw 24 is threaded through 65 an opening in the eccentric bearing 16 as clearly shown in Figure 4, and is adapted to be received by the adjacent hollow lug 16 of the shaft bearing, so that the parts will be maintained in proper operative relation 70 by tightening the adjusting screw 24. Associated with this adjusting screw is a lock nut 25. It will also be noted upon inspection of Figure 4, that the housing 19 for the eccentric bearing is provided with an oil receiving cup 26 having a pivoted cover 27, the cup communicating with an opening 28 which directs the oil onto the periphery of the eccentric bearing 17. Rising from the housing 19 at a point adjacent said cup is a lug 29 which is connected to one end of a tie rod 30, the other end of said rod being connected with the supporting structure for the band wheel indicated generally at C in Figure 1.

The sand reel shaft 10 is mounted for rotation within its bearing 11, so that the wheel and shaft can rotate in one direction to unwind the sand line usually employed with said reel, but not herein shown. By 90 reason of the construction, illustrated, the sand reel can be conveniently shifted into engagement with a brake "not shown", which is usually arranged in juxtaposition to the reel to check or retard the rotation of the 95 reel in the direction just mentioned. When it is desired to rotate the sand reel in an opposite direction for the purpose of winding the cable thereabout, the said reel B can be conveniently shifted into contacting engagement with the band wheel A, the latter being utilized to rotate the reel in the desired direction. For this purpose I make use of a vertically disposed lever 31 which may be secured to the eccentric bearing 17 in any 100 suitable manner or form an integral part thereof. In this connection it is desired to be stated that the eccentric bearing 17 is held associated with the housing 19 by a flange 32 forming an integral of an eccentric bearing and adapted to engage one side of 105 the housing as shown in Figure 2, while a 110

removable flange 33 is arranged at the opposite side of the housing and secured thereto by means of bolts or the like 34. The flange 32 is preferably formed with an offset arm 35 upon which the lever is mounted and held secured thereto by means of a fastening element 36. A manually operating element 40 projecting from the vertically disposed lever 31 so that the sand reel can be shifted in the manner above described, from a remote point.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

The combination with a shaft, of a bear-

ing therefor, lugs projecting from the opposite sides of said bearing, hollow lugs projecting from the top and bottom of said bearing, an eccentric bearing adapted to receive said shaft bearing, lugs projecting inwardly from the opposed sides of the eccentric bearing and engaging the ends of the first mentioned lugs of said shaft bearing, an additional lug depending from the top of the eccentric bearing and received by the adjacent hollow lug of the shaft bearing, an adjusting screw supported by the eccentric bearing diametrically opposite the last mentioned lug thereof, and adapted to be received by the adjacent hollow lug of the shaft bearing, said eccentric bearing having spaced recesses in the periphery thereof, antifriction rollers arranged in said recesses, and a housing for said bearing.

In testimony whereof I affix my signature.

FRANK REDICK.
